CLOSURE STRUCTURE WITH SPRAYING DEVICE

Paul W. Thayer, Minneapolis, Minn.

Application June 4, 1936, Serial No. 83,478

9 Claims. (Cl. 48—87)

This invention relates to a closure structure, and particularly to a closure structure for a retort. While the invention might have various applications, it particularly is designed for use in connection with the generator of a gas making apparatus.

As is well known in the art, in such apparatus a generator is used and usually in connection with a carbureting chamber and a superheater. A body of fuel is heated in the generator and steam is passed through this fuel to be disassociated and produce hydrogen and carbon monoxide. This gas is enriched or carbureted by spraying oil, tar or some hydrocarbon fluid thereinto. The top of the generator is usually open so that the fuel can be charged thereinto and some sort of a closure member is used for the top of the chamber which extends vertically in the generator. It has heretofore been the custom to project the oil into the top of the generator from some side thereof or into the passage leading to the carburetor from one side of said passage. It has been realized that this is not the best place from which to project the oil. The ideal place in which to project the oil or hydrocarbon fluid would be to spray the same downwardly in a shower into the generator and substantially from the center thereof.

It is an object of this invention, therefore, to provide a closure structure for a retort or generator together with means for projecting oil or hydrocarbon fluid downwardly into the generator and centrally thereof.

It is a further object of the invention to provide a closure member for a retort or generator which is movable for charging said retort or generator, together with means for supplying a gaseous medium under pressure and oil to said closure member and projecting a mixture of the same downwardly from said closure member when the same is in closing position.

It is another object of the invention to provide a closure structure for a retort or generator comprising a disk-like plate, a supporting means on which said plate is mounted for universal movement, said means having a chamber therein, means for supplying oil to said chamber and means for supplying steam under pressure to said chamber, a mixture of said oil and steam being projected downwardly from said plate substantially centrally thereof.

It is more specifically an object of the invention to provide a closure structure for a retort or generator comprising a closure member, a supporting means comprising a ball upon which

said closure member is carried for universal movement, said ball having a chamber therein, a rigid conduit extending into said chamber adapted to conduct steam under pressure, a valve means for controlling the passage of steam through said conduit, a flexible conduit secured to said first mentioned conduit for supplying said steam thereto, a second flexible conduit secured to said supporting means for supplying oil to said chamber, said ball and closure member having openings in their bottoms through which a mixture of said steam and oil is sprayed downwardly.

These and other objects and advantages of the invention will be fully set forth in the following description made in connection with the accompanying drawings, in which like reference characters refer to similar parts throughout the several views and in which:

Fig. 1 is a view partly in vertical section and partly in side elevation illustrating the invention;

Fig. 2 is a top plan view of the parts shown in Fig. 1;

Fig. 3 is a view taken on line 3—3 of Fig. 4 as indicated by the arrows;

Fig. 4 is a vertical section taken on line 4—4 of Fig. 3 as indicated by the arrows;

Fig. 5 is a vertical section taken substantially on line 5—5 of Fig. 2 as indicated by the arrows 30 and shown on an enlarged scale;

Fig. 6 is a vertical section taken on line 6—6 of Fig. 2 as indicated by the arrows;

Fig. 7 is a partial view similar to Fig. 5 showing the parts in a different position; and

Fig. 8 is a horizontal section taken on line 8—8 of Fig. 7 as indicated by the arrows.

Referring to the drawings, the upper portion of a generator of a gas making apparatus is shown, of which it will only be necessary to consider the casing member 10 which forms the top of the generator and has the central opening 10a therein. Member 10 is made hollow so that a cooling fluid may be circulated therein and the same has a projecting ledge-forming flange 10b 45 of annular form extending about the opening 10a. A shell 11 has a flange 11a projecting outwardly from its upper end resting on the flange 10b. The fuel for the generator is discharged into the top of shell 11 and passes therethrough to the fuel bed. The casing 10 is held in place by lugs 12 which extend over a flange 10c on member 10, which flange rests on the supporting plate 13. Headed and nutted bolts 14 extend through plate 13 and the lugs 12. Member 10 also has secured 55

therein a comparatively thin steel ring 15 which projects upwardly therefrom at its top. A closure member 16 is provided shown in the general form of a circular disk, said disk having a bottom 5 flat annular surface adapted to seat on the ring 15. The plate 16 is carried by a supporting means comprising a member 17. Member 17 has a ball 17a at its lower end which is disposed in a recess or chamber 16a in member 16. A pair of plates 10 18 are secured to the top of member 16 by the headed and nutted bolts 19, said plates extending closely around ball 17 well above the horizontal diametral plane thereof so that plate 16 is supported on the ball 17a and can have universal 15 movement thereabout. Plate 16 has a frusto-conical and downwardly flaring opening 16b extending from chamber 16a. The ball 17a has a chamber 17b therein of cylindrical form, the same being shown as having a semi-spherical bottom 20 and a small downwardly flaring opening 17c extends through the bottom of the ball from chamber 17b. Chamber 17b has an enlarged cylindrical portion 17d in member 17 above ball 17a, the upper portion of which is interiorly threaded. A 25 cylindrical chamber or countersunk portion 17e of larger diameter than portion 17d is formed in member 17 at its upper end. Member 17 has a chamber or passage 17f cored therein and a bored passage 17g extends from the outer side of member 17 into chamber 17f. Another small passage 30 17h is bored from passage 17f into the cylindrical chamber 17d tangentially of the latter. A small apertured nozzle or plug 20 is threaded into passage 17h, the same having a shoulder-forming 35 collar thereon and an angular head at the outer side of said collar. Member 17 has a projection with a flat surface 17i thereon at one side through which extends opening 17g and a plug 21 is threaded into opening 17g, said plug also having 40 a shoulder-forming collar thereon engaging surface 17i and having an angular head at the outer side of said collar. Member 17 has a plurality of tapped holes 17j extending downwardly thereto, the same having their axes substantially 45 radial to the top semi-spherical surface of member 17. One of these tapped holes 17j as shown in Fig. 5 communicates with the chamber 17f. A plug 22 is secured in the threaded passage 17d, the same having a collar 22a thereon seated on 50 the bottom of chamber 17e. Member 22 has a reduced and exteriorly threaded upper portion 22b on which is threaded the coupling collar 23, the same having a cylindrical top opening and an inwardly projecting flange extending over the 55 outwardly projecting collar of member 24. Member 24 has a downwardly tapered frusto-conical end adapted to seat in an upwardly flaring frusto-conical recess in the top of member 22. If desired, packing material may be disposed between 60 members 22 and 24 and about a central tube or conduit 25 exteriorly threaded and on which member 24 is threaded. Conduit 25 extends downwardly through and fits in a central bore in member 22 and extends to the lower end of 65 chamber 17b. A member 26 has a reduced exteriorly threaded portion screwed into the lower end of member 25 and has its outer side substantially flush with the outer side of member 25. Member 26 has an upwardly flaring frusto-conical recess 26a in its upper end communicating 70 with a downwardly flaring frusto-conical recess 26b in its lower end. A collar 27 is threaded on tube 25 and extends over and downwardly around member 24. A T member 28 is threaded onto the top of tube 25 and receives at its upper end 75

the interiorly threaded collar or coupling member 29 having an inwardly extending flange 29a at its top projecting over an outwardly extending flange 30a on a member 30 which rests on the top of member 28 and has a portion extending a short distance into member 28. Member 30 is centrally bored and threaded to receive a threaded valve rod 31 which extends centrally through members 25 and 28 and has adjacent its lower end a spider member 31a having arms fitted in and guided in the cylindrical bore of member 25. A valve stem 31b extends below spider 31a and has an inverted conical portion 31c at its lower end adapted to move in recess 26b as rod 31 is screwed upwardly or downwardly so as to 15 make larger or smaller the passage through member 26. Rod 31 has a hand wheel 32 secured to its upper end. The upper end of member 30 is exteriorly threaded to receive a packing cap 33 which engages a packing gland 34 slidable in a 20 cylindrical bore in the upper end of member 30 and having a downwardly flaring recess in its lower end. Packing material 35 can be placed around rod 31 in said latter bore and compressed therein by member 34. A flexible conduit 36 is 25 secured to the side of T member 28 and adapted to supply a gaseous medium under pressure, such as steam, to member 28.

Member 17 has a cap or supporting member 38 secured thereto by headed bolts 39 which pass 30 through bored lugs on member 38 and are screwed into the tapped holes 17j. Member 38 has a central opening through which member 22 passes. Member 38 has a bore 38a extending through the lug in alignment with the tapped holes 17j which 35 is in alignment with chamber 17f. A tube 39 which is exteriorly threaded extends through bore 38a and is screwed into said last mentioned hole 17j. A nut 40 is threaded on tube 39 and engages the top of member 38. Tube 39 has a 40 cylindrical passage extending therethrough and a coupling member 41 is threaded onto the upper end of said tube holding in place the enlarged end 42a of a coupling member 42. Portion 42a has a semi-spherical end seated in a semi- 45 spherical recess in the end of tube 39. A flexible tube 43 will be secured to the coupling member 42 and will lead to a suitable supply of oil or other hydrocarbon liquid. This liquid will thus be supplied through tube 39 to the chamber 17f. 50

Member 17 has an arm 17k extending laterally therefrom and having a lug 17m pivoted by pivot member 44 to a bracket 45 which will be suitably mounted at the top of the gas making apparatus. Arm 17k has an end boss 17n bored to receive a 55 plunger rod 46 having a collar 47 secured thereto and engaging the bottom of lug 17m. The upper end of rod 46 is threaded to receive a nut 48 which engages a washer 49 at the top of lug 17n.

In operation, when the top of the generator is 60 closed in the use of the gas making apparatus, closure member 16 occupies the position shown in Fig. 1 and the generator which has its top opening through the shell 11 is closed by engagement of member 16 with the ring 15. When the generator is to be charged with fuel bracket 17k is 65 swung about its pivot or trunnion 44 by depression of rod 46. In practice rod 46 forms the plunger rod of a piston in a steam cylinder and is drawn downward by said piston. This elevates 70 the other end of arm 17k and lifts member 38 together with cover 16. Arm 17k is then swung about the axis of plunger rod 46 so that member 16 is swung out of alignment with shell 11. Fuel 75 can now be charged into the generator through

shell 11. After this arm 17a is again swung to bring plate 16 over shell 11 and rod 46 is elevated by its piston in the steam cylinder cover plate 16 is thus lowered with considerable force and impact against ring 15. Ring 15 is, as stated, of small thickness and acts somewhat as a knife edge to cut through any tar or other material which might have lodged thereon. Plate 16 is free to move about the ball 17a and thus finds a firm and accurate seat on the ring 15.

When it is desired to discharge the oil or hydrocarbon fluid into the generator for enriching or carbureting the gas, steam is supplied through conduit 36. This passes into member 28, down through tube 25, through the valve opening in member 26 and into chamber 17b. Oil is supplied through conduit 43, the same passing through tube 39 into the recess 17f, thence through the nozzle plug 20 and passes tangentially into chamber 17d. The oil is projected in a comparatively fine jet and is given a circular motion in chamber 17d and in chamber 17b. This projected oil which is sprayed and divided as it leaves member 26, meets the steam issuing through member 26 and is mixed therewith and the mixture is projected through opening 17c, ball 17a with this opening forming a nozzle for the projection of said mixture. The mixture is projected downwardly through opening 16b in an expanding conical shower and is thus projected throughout substantially the entire area of the generator chamber. The oil is thus very finely divided and distributed uniformly through the ascending body of gas. The gas and finely divided particles of oil pass into the carburetor where the hydrocarbon gases are fixed.

The amount of steam used can be nicely regulated by manipulating the hand wheel 32 which moves the valve 31c and causes a larger or smaller opening in the passage through member 26. The member 25 may be adjusted upwardly or downwardly in member 22 to bring member 26 farther from or closer to the bottom of chamber 17b. This will regulate the amount of oil sprayed. The closer member 26 is to the bottom of chamber 17b the smaller will be the amount of oil sprayed. After member 25 is thus adjusted to suit the proper amount of oil the spray can be regulated, as stated, by manipulating hand wheel 32 and adjusting valve member 31c. Instead of using flexible conduits extending to member 28 and to member 39, rigid conduits could be used which would have a swivel connection moving about the axis of rod 46.

From the above description it is seen that applicant has provided a simple and efficient closure structure and a structure by means of which the fluid hydrocarbons may be sprayed effectively into the generator chamber. It is apparent that the device will have a high degree of utility for the purpose intended.

It will, of course, be understood that various changes may be made in the form, details, arrangement and proportions of the parts, without departing from the scope of applicant's invention, which generally stated, consists in a device capable of carrying out the objects above set forth in the parts and combinations of parts disclosed and defined in the appended claims.

What is claimed is:

1. A closure structure for a retort having in combination, a disk-like member adapted to extend over an opening in said retort, a ball on which said member is carried, a supporting means for said ball, said ball having a chamber therein

with a discharge opening leading from its lower end and means for delivering a gaseous fluid and oil to said chamber which is mixed therein and delivered through said opening.

2. A closure structure for a retort having in combination, a closure member, a supporting means for said member comprising a ball on which it is carried for universal movement, said ball having a chamber therein with an opening leading from the bottom thereof, a valve-carrying member extending into said chamber, a conduit for supplying a gaseous fluid to said member, a conduit for supplying oil to said chamber whereby mixed oil and fluid are discharged through said opening. 15

3. A retort structure having in combination, a closure plate, a member on which said plate is mounted for universal movement comprising a ball, said ball having a chamber therein, a conduit for the passage of a gaseous medium under pressure secured to said ball and extending into said chamber, means for controlling the passage of said medium through said conduit, a flexible conduit secured to said first mentioned conduit, a flexible conduit secured to said first mentioned member for supplying oil to said chamber, said ball having an opening through its bottom from said chamber through which a mixture of said medium and oil is discharged. 25

4. The combination with a retort having a vertically extending chamber therein with an opening at its top, of a closure member for said opening movable to permit charging of said retort, a second member on which said member is mounted for universal movement, said second member having a central chamber therein and having a second chamber therein at one side of said central chamber, means for delivering oil from said second chamber tangentially into said central chamber, means for delivering oil to said second mentioned chamber and means for delivering a gaseous fluid under pressure to said central chamber, said second member having an opening leading from said central chamber through which a mixture of said fluid and oil are projected downwardly into said first mentioned chamber. 40

5. A closure structure for a retort having in combination, a closure member adapted to extend over an opening in said retort and having an opening in its bottom, a second member on which said member is mounted for universal movement having a chamber therein, means for delivering oil to said chamber, means for delivering a gaseous fluid under pressure to said chamber, said chamber having an opening leading to the bottom of said second member through which a mixture of said oil and fluid is projected through said first mentioned opening. 55

6. The combination with a retort having a vertically extending chamber therein with an opening at its top, of a movable closure member for said opening, a support for said closure member relative to which it is universally movable and means carried by said support for discharging finely divided oil in a shower downwardly into said chamber substantially centrally thereof. 65

7. The combination with a retort having a vertically extending chamber therein with an opening at its top, of a closure member for said opening, a supporting member having a ball disposed in said closure member about which the latter is universally movable, said supporting member having a chamber therein and having an enlarged portion above said ball with a semi-spheri- 70 75

cal top surface, a swinging arm having an end portion with a semi-spherical lower surface engaging said first mentioned surface, means connecting said supporting member and arm, a conduit extending into said supporting member for delivering fluid under pressure into said last mentioned chamber and a conduit connected to said supporting member for delivering oil into said last mentioned chamber, said oil and fluid being mixed in said supporting member and discharged downwardly therefrom into said first mentioned chamber.

8. The combination with a retort having a vertically extending chamber therein with an opening at its top, of a closure member for said opening, a supporting member connected to said closure member about which the latter is universally movable, said supporting member having a chamber therein and having an enlarged portion above said closure member, a movable arm having an end portion connected to said enlarged portion, a conduit extending centrally vertically into said supporting member for delivering fluid under pressure into said last mentioned chamber.

ber, a valve for controlling the discharge of said fluid from said conduit, a conduit connected to said supporting member for delivering oil to said last mentioned chamber, said supporting member having an opening in its lower end through which said fluid and oil are delivered downwardly, said closure member having an opening through which said oil and fluid are delivered downwardly into said first mentioned chamber.

9. The combination with a retort having a vertically extending chamber therein with an opening at its top, of a movable closure member for said opening, a supporting means for said closure member comprising a ball disposed centrally of said closure member, said ball having a chamber therein with a comparatively small opening leading from the bottom thereof, said closure member having an opening therethrough vertically aligned with said opening in said ball and means for delivering oil to said chamber and projecting the same downwardly in finely divided condition in a shower into said chamber.

PAUL W. THAYER.
